(Cl. D61—1)

Fig. 1.

Fig. 2.

Fig. 1 is a rear perspective view of a slide viewer showing our new design; and

Fig. 2 is a side elevational view, the opposite side being substantially a mirror image thereof.

The front, not shown, is conventional.

Portions of the drawing figures have been diagonally lined to indicate translucency.

We claim:

The ornamental design for a slide viewer, as shown and described.
